(57) **CLAIM**

The ornamental design for a controller hatch cover, as shown and described.

DESCRIPTION

FIG. 1 is an exploded perspective view of a controller hatch cover showing the new design;

FIG. 2 is a perspective view thereof;

FIG. 3 is a top plan view, thereof;

FIG. 4 is a front elevational view, thereof;

FIG. 5 is a left side elevational view, thereof;

FIG. 6 is a right side elevational view, thereof;

FIG. 7 is a bottom plan view, thereof;

FIG. 8 is a rear elevational view, thereof;

FIG. 9 is a perspective view, thereof, the paddles being removed;

FIG. 10 is a top plan view of FIG. 9;

FIG. 11 is a front elevational view of FIG. 9;

FIG. 12 is a left side elevational view of FIG. 9;

FIG. 13 is a right side elevational view FIG. 9;

FIG. 14 is a bottom plan view of FIG. 9;

FIG. 15 is a rear elevational view of FIG. 9;

FIG. 16 is a perspective view thereof, shown in an environmental use;

FIG. 17 is a top plan view of FIG. 16;

FIG. 18 is a rear elevational view of FIG. 16;

FIG. 19 is a front elevational view of FIG. 16;

FIG. 20 is a perspective view thereof, with paddles removed and shown in an environmental use;

FIG. 21 is a top plan view of FIG. 20;

FIG. 22 is a back view of FIG. 20; and,

FIG. 23 is a front view of FIG. 20.

In the figures, the broken lines indicate unclaimed portions and environment and form no part of the claimed design.
